Primary Examiner — Mary Ann Calabrese(74) Attorney, Agent, or Firm — Tutunjian & Bitetto, P.C.(57) CLAIM

The ornamental design for a table as shown and described.

DESCRIPTION

FIG. 1 is a top perspective view of the table showing our new design;
FIG. 2 is a front view thereof;

FIG. 3 is a rear view thereof;

FIG. 4 is left side view thereof;

FIG. 5 is a right side view thereof;

FIG. 6 is a top view thereof; and,

FIG. 7 is a bottom view thereof.

The broken lines in the drawings depict structure that makes up no part of the claimed design.
